UNITED STATES PATENT OFFICE.

REUBEN B. BENJAMIN, OF CHICAGO, ILLINOIS, ASSIGNOR TO BENJAMIN ELECTRIC MFG. COMPANY, OF CHICAGO, ILLINOIS, A CORPORATION OF ILLINOIS.

MOISTURE-PROOF TWIN SOCKET.

1,102,640.

Specification of Letters Patent.

Patented July 7, 1914.

Application filed September 14, 1912. Serial No. 720,395.

To all whom it may concern:

Be it known that I, REUBEN B. BENJAMIN, a citizen of the United States, residing at Chicago, in the county of Cook and State of Illinois, have invented new and useful Improvements in Moisture-Proof Twin Sockets, of which the following is a full, clear, concise, and exact description, reference being had to the accompanying drawing, forming a part of this specification.

My invention pertains to twin sockets for incandescent electric lamps; *i. e.*, sockets of the kind which support two lamps in axial alignment pointing in opposite directions.

In some instances, as, for instance, for use in connection with bath cabinets and the like, it is desirable to protect the socket to the greatest possible extent against the effects of moisture and moist gases; and it is the principal object of my invention to provide a twin socket which will be moisture proof to a high degree.

It is a further object of my invention to provide a twin socket of a simple and economical construction, which will be durable even though used in moist places, and which may be readily removed and taken apart.

With these and other objects in view, I have constructed a twin socket, described in the following specification and shown in the accompanying drawings. It is to be understood, however, that my invention may take other forms than that shown and described, without exceeding the scope thereof as defined in the appended claims.

In the drawings Figure 1 is a longitudinal section through the socket; Fig. 2 is an end view of the socket as seen from the left hand end of Fig. 1; Fig. 3 is a section taken on the line 3-3 of Fig. 1, looking in the direction of the arrows; Fig. 4 is a section on the line 4-4 of Fig. 1, looking in the direction of the arrows; and Fig. 5 is a section on the line 3-3 of Fig. 1, but looking in the direction opposite to that indicated by the arrows.

Like reference characters refer to like parts throughout the following specification and the several figures of the drawings.

Referring now particularly to Fig. 1, 10 indicates an open-ended tubular metallic casing of such a length as conveniently to receive the bases of two lamps, and provided with the ordinary beads 11, one at each end.

15 A shouldered bushing 12 passes through the

casing 10 at the center thereof, and is flanged over, at 13, within the casing, a substantially rectangular washer 14 being clamped between the flange of the bushing and the interior surface of the casing. The bushing 12 is formed with interior screw threads, and is provided with the ordinary cap screw 15, and serves to connect the casing with a conduit in the ordinary manner. Mounted within the casing 10 and secured against withdrawal therefrom by their engagement with the ends of the washer 14, is a pair of lamp receptacles, each of which includes a cup-shaped insulating member of sufficient capacity entirely to contain both contacts of each receptacle. One of these cup-shaped insulating members, that shown at the right hand side of Fig. 1, is designated 16 in the drawings. The rear wall 17 of the insulating member 16 is formed with a recess in which lies a binding terminal 18 (Fig. 3) which is entered by the end of a screw 19, which passes through the wall 17 and also through a bridge plate 20 upon the front side of the wall 17. Beneath this bridge plate is clamped a flange 21 formed at the inner end of a threaded lamp-receiving shell 22, contained in the member 16. The flange 21 is cut away so as to accommodate a boss 23 formed upon the front side of the wall 17 and serving to provide a solid back for the center contact of the lamp receptacle. The end of the screw 19 is preferably soldered, as shown at 24 (Fig. 3), so as to provide a good moisture proof electrical connection between the shell 22 and the binding terminal 18. The rear side of the end wall 17 of the member 16 is formed with a second recess in which lies a binding terminal 25, secured in place by means of a screw 26 passing through the same and through the wall 17 from front to rear thereof. The front of the wall 17 is formed with a recess 27 for accommodating the head of the screw 26. A pair of metallic strips, 28 and 29 respectively, are clamped between the binding terminal 25 and a nut 30 upon the end of the screw 26, a solid connection being made between the nut and the end of the screw in order to insure a good moisture proof electrical connection between the strips 28 and 29 and the binding terminal 25. The strip 28 passes through a flat slot 31 formed between the front and rear sides of the wall 17, and is bent up, within

the member 16, to form a center contact 32 coöperating with the threaded shell 22, the shell 22 being cut away, as at 33, to obviate any chance of a short circuit owing to the center contact and shell contact making connections with each other.

The wall 17 has two holes 34 formed therethrough which align with similar holes in the flange 21 of the shell contact 22, corresponding holes being also formed in the bridge plate 20. The second cup-shaped insulating member 16^a is a duplicate of the member 16, and has a rear wall 17^a and base 23^a, similar to the rear wall 17 and base 23 of the member 16. Located within the member 16^a is a shell contact 22^a similar to the contact 22, this contact being held in position by means of screws 35 passing through its flange 21^a and through the holes 34, and entering the ends of the bridge plate 20. By this means, not only is the shell contact 22^a retained in position, but the two receptacles are clamped together back and back. In order to separate the members 16 and 16^a of the two receptacles somewhat, these members are formed with recesses 36 and 36^a, the ends of which engage against the ends of the washer 14. When, therefore, the screws 35 are in position, the two lamp receptacles are secured together, back to back, with a small space between them; and the engagement of the ends of the recesses 36 and 36^a with the ends of the washer 14 prevents the lamp receptacles from being withdrawn from the casing 10. The center contact 32^a, coöperating with the shell contact 22^a, is formed by the upturned end of the strip 29 which passes through a slot 31^a similar to the slot 31. The shell contacts 22 and 22^a are thus in electrical connection with each other, as also are the center contacts 32 and 32^a; and the binding terminals 18 and 25 are in electrical connection with these contacts respectively.

The rear side of the rear wall 17 of the insulating member 16 is formed with a channel 37 communicating with the recesses in which are located the binding terminals 18 and 25. This channel faces a similar channel 37^a formed in the rear wall 17^a of the member 16^a, the two channels producing a substantially tubular passage, permitting the lead conductors entering through the bushing 12 to be brought to the terminals 18 and 25. It will be seen that the conducting parts of the socket are all insulated from each other and from the casing by solid porcelain or similar material, no fiber or other mate-

rial which would be deteriorated by moisture being employed. The socket is thus rendered capable of use under conditions where moisture is present in large quantities; and it is not liable to become deteriorated by reason of its use under such conditions. The socket may be easily assembled and taken apart, all that is necessary to take the socket apart being to withdraw the screws 35 and to bend down the center contact 32^a, whereupon the lamp receptacles may be pulled out endwise from the casing 10, the center contact 32^a passing through the passage 31^a. The construction is simple, and the device can be placed on the market at a low cost.

Having thus described my invention, what I claim as new and desire to secure by Letters Patent, is—

1. In a moisture proof twin socket, the combination with a tubular open-ended metallic casing, of two threaded lamp-receiving contacts arranged back to back, two center contacts arranged back to back, and vitreous means for supporting said contacts, said means being disposed between said contacts and surrounding said threaded contact so as to insulate the same from said casing.

2. In a moisture proof twin socket, the combination with a tubular open-ended casing having a projection therein, of a pair of lamp receptacles mounted therein, each of said lamp receptacles including a cup-shaped member formed of vitreous material and a threaded contact and a center contact contained therein, and means for securing said receptacles back to back so as to clamp said projection between them, thereby to retain said receptacles in said casing.

3. In a moisture proof twin socket, the combination with a tubular open-ended casing, of a pair of cup-shaped insulating members mounted therein, each of said members having a passage formed through the rear wall thereof, a pair of center contacts secured to the rear side of the rear wall of one of said members, one of said center contacts passing through each of said passages and entering said members, a threaded lamp-receiving contact carried by each of said members, and means for making electrical connection between said last named contacts.

In witness whereof, I have hereunto subscribed my name in the presence of two witnesses.

REUBEN B. BENJAMIN.
